UNITED STATES PATENT OFFICE

CHARLES W. JENKINS, OF RICHMOND, VIRGINIA.

IMPROVEMENT IN STEEL BRUSHES FOR CLEANING CASTINGS.

Specification forming part of Letters Patent No. **158,498**, dated January 5, 1875; application filed July 8, 1874.

To all whom it may concern:

Be it known that I, CHARLES W. JENKINS, of Richmond, in the county of Henrico and in the State of Virginia, have invented certain new and useful Improvements in Steel Brushes for Cleaning Castings; and do hereby declare that the following is a full, clear, and exact description thereof, reference being had to the accompanying drawings and to the letters of reference marked thereon, making a part of this specification.

The nature of my invention consists in the construction of a brush for foundry purposes, the peculiarities of which will be hereinafter set forth.

In the annexed drawings, Figure 1 represents a side view of my brush; Fig. 2, a plan view of the body, with the hinged top thrown up. Fig. 3 is a cross-section, and Fig. 4 represents one of the groups of wire which form the brush.

In the drawings, A represents the body of the brush, which may be made of wood or other suitable material. This body is provided with a series of conical holes to receive the wire, as will be described. B represents a hinged top, which lies upon the heads of the wire groups, and confines them in place. D represents a group of wire pieces, which may be round or square or other shape, which are

cut of suitable length, and bent, as seen in Fig. 3, and their ends brought together again. At the centers of these wires, where they are bent, a conical metal head is formed by casting lead or other suitable metal around them. This conical head fits in the conical opening in the body of the brush, the ends projecting through and forming a brush, as seen in Fig. 1. These groups are held in place by the hinged top B.

When said top is raised, any or all of the groups may be removed, and thus the brush mended or made anew.

This brush is used more particularly for cleaning castings, and for such rough work.

Having thus fully described my invention, what I claim as new, and desire to secure by Letters Patent, is—

The body A, provided with conical openings, in combination with the groups D and their conical heads, and the cover B, as and for the purpose set forth.

In testimony that I claim the foregoing I have hereunto set my hand this 26th day of June, 1874.

CHARLES W. JENKINS.
